UNITED STATES PATENT OFFICE.

ROBERT SAYER ASPINWALL, OF DETROIT, MICHIGAN.

DESIGN FOR A LIGHTING-FIXTURE.

56,848.

Specification for Design.

Patented Jan. 4, 1921.

Application filed July 28, 1920. Serial No. 399,630. Term of patent 3½ years.

To all whom it may concern:

Be it known that I, ROBERT SAYER ASPINWALL, a citizen of the United States of America, residing at Detroit, county of Wayne, State of Michigan, have invented a new, original, and ornamental Design for a Lighting-Fixture, of which the following is a specification, reference being had to the accompanying drawing, forming a part thereof.

The figure of the drawing is an elevation of my lighting fixture.

The lighting fixture as shown is adapted to be suspended from the ceiling, the canopy shown at the top of the chain being secured thereto.

What I claim is:

The design for a lighting fixture as shown in the drawing.

ROBERT SAYER ASPINWALL.
